Maude Sinclair George Inventor

By Lawrence A. Alton Jr. Attorney

UNITED STATES PATENT OFFICE.

MAUDE SINCLAIR GEORGE, OF ST. LOUIS, MISSOURI.

DESIGN FOR A GARMENT PROTECTOR.

• 61,295.

Specification for Design.

Patented Aug. 1, 1922.

Application filed April 8, 1922. Serial No. 1,638. Term of patent 14 years.

To all whom it may concern:

Be it known that I, MAUDE SINCLAIR GEORGE, a citizen of the United States of America, residing at St. Louis, in the county of St. Louis and State of Missouri, have invented a new, original, and ornamental Design for Garment Protectors, of which the following is a specification, reference being had to the accompanying drawings forming a part thereof.

What is claimed is:

The ornamental design for the garment protector, as shown.

MAUDE SINCLAIR GEORGE.
